UNITED STATES PATENT OFFICE.

FRANCIS J. COLE, OF SCHENECTADY, NEW YORK.

DRIFTING-VALVE FOR LOCOMOTIVES.

1,106,081.

Specification of Letters Patent. Patented Aug. 4, 1914

Application filed June 6, 1914. Serial No. 843,348

To all whom it may concern:

Be it known that I, FRANCIS J. COLE, of Schenectady, in the county of Schenectady and State of New York, have invented a certain new and useful Improvement in Drifting-Valves for Locomotives, of which improvement the following is a specification.

My present invention is an improvement upon that for which Letters Patent of the 10 United States No. 1,089,804, were granted and issued to me under date of March 10, 1914, and its object is to effect a simplification of the mechanism set forth therein, while attaining, with equal effectiveness, the 15 same result of automatically admitting a limited quantity of steam, directly from the boiler, to the valve chests and cylinders of a locomotive engine, during the periods in which the locomotive is "drifting," or running with its throttle closed, in order to prevent the formation of a vacuum in the cylinders, and lubricate them to prevent overheating and wear of the parts which are in frictional contact.

25 The improvement claimed is hereinafter fully set forth.

In the accompanying drawings Figure 1 is a diagrammatic side view of a locomotive engine, illustrating an application of my invention; Fig. 2, a vertical central section through the drifting valve mechanism; Fig. 3, a side view, in elevation, taken at a right angle to Fig. 2; and, Fig. 4, a horizontal section, on the line *a a* of Fig. 2.

35 In the practice of my invention, I locate in any convenient position, preferably, as shown, within the cab of the locomotive, a diaphragm chamber, 2, which is in the form of a short polar section of a sphere, and is 40 open at its bottom, across which there extends a flexible diaphragm, 4, which is secured, at and adjoining its periphery, to the chamber, 2, by a cover plate, 5, having one or more air admission openings, 5^a, and connected to the chamber by bolts, 5^b, and nuts, 5^c. The joint between the diaphragm and the chamber is hermetically sealed, and the cover plate prevents distortion of the diaphragm, in the event of the accumulation of 45 pressure in the chamber, when the locomotive is working under steam. A steam supply chamber, 6, and a steam delivery chamber, 7, are formed centrally in the upper portion of the diaphragm chamber, 2, and are 50 separated by a partition, 8, in which there is formed an opening controlled by a hollow

double seated steam supply valve, 9, of the puppet type, which closes downwardly, or in the direction of the steam delivery chamber, on seats formed in the partition, 8, and in the bottom of the delivery chamber. The valve, 9, is inserted in the supply chamber through an opening in its top, closed by a screw plug, 6^a. The steam supply chamber, 6, communicates, by a pipe, 10, with a turret or small steam dome, 10^a, on the boiler, and a pipe, 12, leads from the steam delivery chamber, 7, to the outside steam pipe, 1^a, or to the valve chest, 1, which communicates therewith, as preferred. A bearing plate, 16, rests on the top of the diaphragm, 4, and is provided with a central socket, 16^a, which fits around a cylindrical guide, 2^a, depending from the top of the diaphragm chamber. An operating stem, 15, fixed to the bearing plate, 16, projects upwardly therefrom into, and fits truly in, the guide, 2^a, said stem carrying at its lower end, a valve, 15^a, adapted to seat in the lower end of the guide, and a stem, 15^b, is fitted in the 75 guide, above the stem, 15, of which it forms an extension, with its lower end adjoining the upper end of said stem, and with its upper end adjoining a transverse bearing plate, 9^a, on the top of the valve, 9. A pipe, 3, 80 leads from the diaphragm chamber, 2, to the valve chest, 1, or to the communicating outside steam pipe, 1^a, as preferred; said pipe being controlled by a check valve, 3^a, which seats downwardly in the diaphragm chamber, 90 and is inserted therein through an opening closed by a screw plug, 3^b, and a drain passage, 17, controlled by an inwardly opening check valve, 17^a, leads from the diaphragm chamber to any convenient point of 85 discharge.

In the operation of the appliance above described, when the locomotive is drifting and a partial vacuum is formed in the valve 100 chests and communicating steam supply pipes, a corresponding reduction of pressure results in each of the diaphragm chambers, above the diaphragm, 4, thereof, which, with the superposed bearing plate, 16, is thereupon forced upwardly by the higher atmospheric pressure below it of the air which enters through the opening, 5^a. The upward movement of the diaphragm, acting directly on the steam supply valve, 9, through the interposed bearing plate, 16, and operating 105 stem sections, 15, 15^b, unseats said valve and admits steam from the boiler through the 110

2

pipe, 10, chambers, 6 and 7, and pipe, 12, to the outside steam pipe, 1^a, or communicating valve chest, 1, accordingly as the pipe, 12, may be connected. When the throttle is 5 opened for the purpose of working the locomotive under steam, the diaphragm, 4, is depressed by the boiler pressure acting on the valve, 9, and said valve is seated, thereby cutting off the independent supply of steam 10 and returning the parts to the normal position shown in Fig. 2. Leakage of steam into the diaphragm chamber is prevented by the valves, 15^c and 15^a, and any water of condensation that may accumulate in the dia- 15 phragm chamber is discharged therefrom through the drain passage, 17. The check valve, 3^a, prevents the vacuum in the dia- phragm chamber from being broken when the locomotive is drifting.

20 I claim as my invention and desire to secure by Letters Patent:

1. In a drifting valve appliance for locomotives, the combination of a diaphragm chamber communicating with a distribution 25 valve chest, a flexible diaphragm closing one end of said chamber and subject to atmospheric pressure on its outer side, a valve controlling the supply of steam from the boiler to a valve chest independently of the main 30 throttle valve, and means, interposed between said valve and the diaphragm, for unseating said valve by the direct action of the upward movement of the diaphragm induced by the formation of a partial vacuum in the 35 valve chest and diaphragm chamber.

2. In a drifting valve appliance for locomotives, the combination of a diaphragm chamber communicating with a distribution valve chest, a flexible diaphragm closing one 40 end of said chamber, and subject to atmospheric pressure on its outer side, a valve controlling the supply of steam from the boiler to a valve chest independently of the main 45 throttle valve, and an operating stem, interposed between and adapted to bear at op-

posite ends on, said valve and the diaphragm, and directly transmit upward movement of the diaphragm, induced by the formation of a partial vacuum in the valve chest and diaphragm chamber, to said valve. 50

3. In a drifting valve appliance for locomotives, the combination of a diaphragm chamber communicating with a distribution valve chest, a flexible diaphragm closing one end of said chamber and subject to atmospheric pressure on its outer side, a valve controlling the supply of steam from the boiler to a valve chest independently of the main throttle valve, means interposed between said valve and the diaphragm for unseating 55 said valve by the direct action of the upward movement of the diaphragm induced by the formation of a partial vacuum in the valve chest and diaphragm chamber, and a check valve interposed between the diaphragm 60 chamber and valve chest and adapted to seat in the direction of the diaphragm chamber.

4. In a drifting valve appliance for locomotives, the combination of a diaphragm chamber communicating with a distribution 70 valve chest, a flexible diaphragm closing one end of said chamber and subject to atmospheric pressure on its outer side, a steam supply chamber and a steam delivery chamber fixed on the top of the diaphragm chamber, a steam supply valve controlling communication between said supply and delivery chamber, a pipe for connecting the steam supply chamber with a locomotive boiler, a pipe for connecting the steam de- 75 80 liver chamber with a distribution valve chest, and an operating stem interposed between the diaphragm and steam supply valve, in line axially therewith, and adapted to transmit vertical movement directly from one of said members to the other. 85

FRANCIS J. COLE.
